COMBINED WINDMILL AND DRUM TOY

Cheung Ngun Lee, 779 Commercial St.,
San Francisco, Calif.

Filed Sept. 16, 1963, Ser. No. 76,601

Term of patent 14 years

(Cl. D34—15)

Fig. 1

FIG. 4FIG. 5FIG. 6

FIGURE 1 is a front elevation of the combined windmill and drum toy showing my new design.

FIGURE 2 is a side elevation thereof.

FIGURE 3 is a bottom plan view of the toy.

FIGURE 4 is a rear elevation of the toy.

FIGURE 5 is a side elevation of the toy when looking at the opposite side from that shown in FIGURE 2.

FIGURE 6 is a top plan view of the toy.

I claim:

The ornamental design for a combined windmill and drum toy, substantially as shown.
